LIP TURNING MACHINE

Carl A. Newhall, Peabody, Mass., assignor to
 United Shoe Machinery Corporation, Paterson,
 N. J., a corporation of New Jersey

Application May 15, 1936, Serial No. 79,955

6 Claims. (Cl. 12—30)

This invention relates to lip turning machines and is herein illustrated and described as embodied in a machine for raising and turning back from the base of the channel the lip of an outsole which may be temporarily attached to a shoe.

It is an object of the invention to provide an improved machine of the type under consideration. In accordance with a feature of the invention there is provided means for raising a channel lip formed on a sole, a tool adapted to extend beneath the raised lip and having a movement of rotary oscillation to turn the raised lip away from the base of the channel, and means for setting the lip in open position. In the illustrated machine the lip-engaging tool exerts a prying action upon the raised lip to open the channel; and the lip-raising means comprises a plow which is oscillated to exert a feeding action upon the sole as the work is presented by the operator. The plow advances at a time when the lip-turning tool is not exerting downward pressure upon the lip and executes its back feed movement at a time when the lip-raising tool presses the lip and thereby the sole downwardly and relieves the frictional engagement between the base of the channel and the plow. The lip-setting member of the illustrated machine operates by pressure upon the turned-back lip to set the lip. This presser member and the plow are both secured to the same support, the presser member moving in unison with the plow. The oscillatory movement above referred to renders the presser member more effective in its setting action upon the lip.

The invention further consists in features of construction and combinations and arrangements of parts hereinafter described and claimed. The invention will be explained with reference to the accompanying drawing, in which

Fig. 1 is a view in perspective of the upper portion of the improved machine;

Fig. 2 is a plan view of the shoe-engaging instrumentalities of the machine in operation upon a channel formed on the outsole of a shoe;

Fig. 3 is a view in elevation of the shoe-engaging members shown in Fig. 2;

Fig. 4 is a view taken in the direction of the arrow A of Fig. 3;

Fig. 5 is a sectional view taken on the line V—V of Fig. 4; and

Fig. 6 is a sectional view similar to Fig. 5 but with one of the operating instrumentalities shown in a different position.

The supporting structure of the machine consists of a frame 10 adapted to stand upon the floor and supporting a head 12. A shaft 14 which is journaled in a bearing formed in the head 12 carries a pulley 16 which may be driven by a belt from any convenient source of power.

Mounted upon the shaft 14 is a head 18 from

which extends a crank pin 20. Mounted upon the crank pin 20 is one end of a connecting rod 22, the opposite end of which connecting rod is mounted upon a pin 24 extending from a crank 26. Extending from the head 12 is a bearing 28 in which is journaled a shaft 30. The crank 26 is secured upon the shaft 30 in any desired position of angular adjustment about the axis of the shaft by means of a clamping bolt 32 which extends through a lug 34 and is threaded into another lug 36. The crank 26 is split and the bolt 32 serves to draw the two portions of the crank 26 together to clamp the crank on the shaft 30. The radial displacement of the crank pin 24 from the axis of the shaft 30 is considerably greater than that of the crank pin 20 from the axis of the shaft 14. In the illustrated machine one complete revolution of the shaft 14 will cause the shaft 30 to oscillate through an angle of about 80°. The head 12 is shaped to enclose the head 18, connecting rod 22, and crank 26, and is provided with a cover plate 38 which may be removed to provide access to these parts.

Secured upon the outer end portion of the bearing 28 is a bracket 40. Extending downwardly from the bracket 40 is a pin 42 upon which is rotatably mounted a sleeve 44. A lug 46 extending from the sleeve 44 has secured to it an integral member consisting of two parts, namely a plow 48 for raising a channel lip and a flat member 50 having a smooth under surface adapted to press down the overturned channel lip. Extending from the sleeve 44 is an arm 52 which is connected through a ball and socket joint 54 to one end of a connecting rod 56. The opposite end of the connecting rod 56 is mounted upon an eccentric pin 58 extending from the end of the shaft 30.

Non-rotatably clamped upon the end portion of the shaft 30 by a screw 60 is a split sleeve 62. An iron 64 extends in a general direction parallel to the axis of the shaft 30 beyond the end of the shaft and of the eccentric pin 58. The outer end of the iron 64 is shaped to enable it to raise the lip of the sole. This end portion of the iron 64 extends downwardly, terminating in a blunt point 66 which is adapted to bear against the shoulder of the channel. Extending upwardly from the point 66 is a blunt edge 68 which, as best shown in Fig. 6, is concave in the vicinity of the point 66. The concavity of the edge 68 straightens out and becomes somewhat convex at the upper portion of the edge 68.

Between the plow 48 and the pressing member 50 is a recess 70 into which the edge 68 and the point 66 extend. The plow 48 has an outer end portion 72 (Fig. 1) which is adapted to serve as a gage against which the shoulder of the channel is held. Beneath the pressing member 50 is a downwardly extending surface 60

14 which likewise constitutes a gage engageable with the shoulder of the channel. The bearing surfaces 72 and 74 and also the point 66 are substantially in the line of the axis of the shaft 5 30.

The operation of the machine upon a shoe S having a channel lip L is illustrated in Figs. 2 to 6, inclusive. Before presenting the shoe to the machine an end portion of the lip is first turned 10 up by hand. The shoe is then held with the shoulder of the channel against the surfaces 72 and 74 with the pressing member 50 extending over the turned lip L. The iron 64 will partake of the oscillatory movement of the shaft 30 and the edge 68 will accordingly oscillate about the point 66 which engages the shoulder of the channel. As the iron 64 is thus oscillated the blunt edge 68 of the lip-raising member will oscillate 15 about the point 66 which, as above indicated, lies substantially in the axis of oscillation, and pry up the lip L to open the channel. The turning or prying action of the edge 68 upon the lip L is illustrated in Figs. 5 and 6, which show the edge 68 in its limiting positions. The concavity 20 of the edge 68 above referred to is provided to avoid sharply creasing the lip at the shoulder. The oscillation of the shaft 30 will also, through the connecting rod 56, cause an oscillation of the sleeve 44 and thereby of the pressing member 50 25 and the plow 48. The angular position of the sleeve 62 upon the shaft 30 is so adjusted in relation to the angular position of the eccentric pin 58 that when the edge 68 is moving from the position shown in Fig. 5 to the position shown 30 in Fig. 6 and is pressing outwardly and downwardly upon the lip L the plow 48 and the pressing member 50 will be moving in a direction opposite to the feed of the work, and when the edge 68 is not bearing outwardly or downwardly upon 35 the lip L the plow 48 and the pressing member 50 will be moving in the direction of feed of the work. As the operator holds the work with upward and inward (i. e. toward the left as viewed in Figs. 5 and 6) pressure against the plow 48 and the pressing member 50 these members in 40 their feeding movements tend to carry the sole along with them, while during the back feed movement of the plow and pressing member the downward and outward thrust of the edge 68 minimizes the frictional engagement between the 45 shoe and the plow 48 and pressing member 50 and thereby overcomes any tendency on the part of those members to retract the shoe in the course of the back feed movement. The oscillatory feed movement of the member 50 causes this member to exert an ironing or smoothing action upon the lip L to set the lip in its turned position. The 50 limiting positions of the movement of the edge 68 may be varied by loosening the screw 60 and readjusting the sleeve 62 about the axis of the shaft 30. The timing of the feeding movement of the plow 48 and the pressing member 50 is adjusted by loosening the screw 34 and turning the shaft 30 relatively to the crank 26. In 55 order to avoid changing the throw of the edge 68 the screw 60 may also be loosened and the sleeve 62 held stationary during this adjustment.

Having thus described my invention, what I claim as new and desire to secure by Letters Patent of the United States is:

1. A machine of the class described comprising a plow for raising a channel lip formed on a sole, a tool adapted to extend beneath the raised lip,

means for imparting to said tool an oscillation about a center which is adjacent to the shoulder of the channel and having a heightwise component relatively to the sole to cause said tool to turn the raised lip away from the base of the channel, and means for setting the lip in open position. 5

2. A machine of the class described comprising means adapted to extend into a channel formed upon a sole for raising the lip of the channel, a tool adapted to engage the raised lip, 10 means for imparting to said tool oscillatory movement having a downward component to turn the raised lip back away from the base of the channel, and means for imparting to said lip-raising means an oscillatory movement in the direction of feed to facilitate feeding the sole. 15

3. A machine of the class described comprising means adapted to extend into a channel formed upon a sole for raising the lip of the channel, a tool adapted to engage the raised lip, means for 20 imparting to said tool oscillatory movement having a downward component to turn the raised lip back away from the base of the channel, and means for imparting to said lip-raising means an oscillatory movement in the direction of feed, 25 the two movement-imparting means being constructed and arranged to cause the advance feed movement of the lip-raising means to take place while the lip-engaging tool is not exerting a downward pressure upon the channel lip and to cause 30 the lip-raising means to execute its back feed movement at a time when the lip is subjected to downward pressure from the lip-engaging tool.

4. A machine of the class described comprising a tool adapted to engage a channel lip, a plow 35 positioned in advance of said tool for raising the lip, means for operating said lip-engaging tool to turn the raised lip away from the face of the channel, a presser member positioned upon the opposite side of said lip-engaging tool from said plow adapted to press downwardly upon the turned-back lip to set the lip, a common support for said plow and said presser member, and means for oscillating said support to cause said plow and said presser member to oscillate lengthwise of the channel. 45

5. A machine of the class described comprising a plow adapted to extend into a channel formed on a sole for raising the lip of the channel, a gage engageable with the shoulder of the raised 50 lip after the lip has been turned over, a member extending inwardly of the sole beyond said gage and having a smooth under surface for holding down the turned-over lip, means located between said plow and said hold-down member for turning over the raised lip, and a common support for said plow, said gage and said hold-down member. 55

6. A machine of the class described comprising two gages adapted to engage the shoulder of a channel formed on a sole at localities spaced lengthwise of the channel, a plow adapted to extend into the channel for raising the lip of the channel, a member provided with a smooth under surface for holding down the channel lip after the lip has been raised and turned over, a tool adapted to extend beneath the raised lip at a locality between said gages, and means for oscillating said tool about an axis which lies substantially in a line joining the two gages to cause the tool to exert a prying action to turn over the raised lip. 65
